UNITED STATES PATENT OFFICE.

CHARLES A. PRATTE, OF DENVER, COLORADO.

ASH-PAN SPRINKLER AND CLEANER FOR LOCOMOTIVES.

Application filed May 4, 1923. Serial No. 636,779.

To all whom it may concern:

Be it known that I, CHARLES A. PRATTE, a citizen of the United States, residing at Denver, the city and county of Denver, and 5 State of Colorado, have invented certain new and useful Improvements in Ash-Pan Sprinklers and Cleaners for Locomotives; and I do declare the following to be a full, clear, and exact description of the invention, such as will enable others skilled in the art to which it appertains to make and use the same, reference being had to the accompanying drawings, and to the characters of reference marked thereon, which 10 form a part of this specification.

This invention relates to ash pan sprinklers and cleaners for locomotives.

Railroad trains, as we all know, are drawn almost exclusively by steam locomotives which burn coal or wood. A locomotive burns a large amount of coal and as a result a large amount of ashes and cinders is produced. It is, of course, not permissible to scatter these ashes and cinders along the 20 road and therefore each locomotive is provided with an ash pan into which the cinders and ashes are received as they drop from the grates. These ash pans are provided with hinged bottoms which can be 25 opened and closed from the engine cab and which are operated whenever the ashes are dumped as they must be at frequent intervals. Before the ashes and cinders are dumped they must be thoroughly drenched 30 so as to prevent them from setting fire to the ties or to other inflammable material in the vicinity. Locomotives are usually provided with some means for sprinkling the ashes with water but in the majority 35 of cases the pipes are so arranged that the intense heat to which they are subjected causes them to burn and become inoperative.

The larger types of modern locomotives 40 are provided with ash pans of great size some of which are eleven feet long and about nine feet wide. These ash pans usually have a longitudinal central depression flanked by outwardly extending substantially horizontal side plates whose upper 45 surfaces are spaced six or eight inches from the bottom of the mud ring. Ashes and cinders dropping from the grates lodge on these plates and unless they are removed

therefrom at frequent intervals the cinders 55 will soon fill the space between the grates and the plates and interfere with the draft and sometimes cause the grates to melt.

It is the object of this invention to provide ash pans of the type referred to with 60 sprinklers which will not only drench the ashes with a spray of water but which are so designed and arranged that they will clean the side plates of ashes and wash the same into the central depressed portion. 65

My invention can be best explained by reference to the accompanying drawing in which—

Fig. 1 is a top plan view of an ash pan equipped with my sprinklers and shows the 70 manner in which the streams of water cover the entire pan surface and clean the same.

Fig. 2, is a section taken on line 2—2 Fig. 1.

Fig. 3 is a side elevation of the pan shown 75 in Fig. 1.

Fig. 4 is a section taken on line 4—4 Fig. 1.

Fig. 5 shows a longitudinal vertical section of another type of ash pan equipped 80 with a sprinkler.

Fig. 6 is a plan view of one of the corner sprinklers, portions thereof being broken away to better show the construction.

Fig. 7 is a side elevation of the sprinkler 85 shown in Fig. 6, looking in the direction of the arrow 7.

Fig. 8 is an elevation of the sprinkler shown in Fig. 6, looking in the direction 90 of the arrow 8.

Fig. 9 is a side elevation of the end or central sprinkler with portions thereof broken away and—

Fig. 10 is an end elevation of the sprinkler 95 shown in Fig. 9 the view being taken looking in the direction of the arrow 10.

The same reference characters will be used to designate the same parts throughout the several views.

Numeral 1 represents the bottom of a 100 locomotive fire box underneath which an ash pan designated as a whole by the numeral 2 is suspended by means of bolts 3. The ash pan shown in Figs. 1, 2 and 3 is typical of the pans employed in connection with locomotives of the larger modern types and comprises a central box like compartment having sides 4 and 5 and a bottom 6 that is pref-

erably so constructed that it can be opened for the purpose of dumping the ashes or cinders. The central compartment extends the entire length of the pan and its ends are closed by plates 7 and 8. Secured to the upper edges of the sides are plates 9 which are of such width that the distance between their outer edges is slightly greater than the width of the grates which are directly above.

10 It is evident that as the cinders and ashes fall through the grates some of them will fall into the central compartment while others will fall onto the tops of the plates 9. As the upper surfaces of plates 9 are slightly inclined the cinders and ashes that fall upon them will remain there and if they are not removed they will soon reach up to the under surface of the grates and obstruct the draft and cause the grates to melt.

15 It is the object of this invention to provide ash pans of the type described with means whereby the attendant in the cab can, by merely opening a valve wash all the cinders from the tops of the plates 9 into the central longitudinal compartment where they may be thoroughly drenched by means of a sprinkler. In each corner of the larger sized ash pans I place a sprinkler 10 which is shown in detail in Figs. 6, 7, and 8. This

20 sprinkler consists of a hollow cast iron box having its end 11 and side 12 placed at right angles to each other and an arcuate portion 13 connecting the side and end in the manner shown in Fig. 6. The arcuate portion has

25 two rows of holes 14 extending radially therethrough. The top 15 extends beyond the arcuate side portion 13 so as to form an overhanging downwardly inclined flange 16. The side 12 is provided with a lug 17 having

30 a hole 18 for the reception of a bolt 19 by means of which the sprinkler is secured to the plate 9. The end 11 of each sprinkler is provided with a threaded opening to which is firmly secured a pipe 20 in the manner shown in Figs. 1 and 3. The pipes 20

35 extend into the cab where they are provided with valves and are connected to the boiler or to the injector line so that when the valves are opened water under full boiler pressure is supplied to the interior of the sprinklers.

40 The water will flow out through the radial holes 14 with great force the streams covering the entire upper surface of the plates 9 in the manner indicated in Fig. 1. Any

45 ashes or cinders that may be on top of the plates 9 will be washed into the central compartment. The sprinklers 10 are located near the outer edge of the ash pan and will not burn out because they are not subjected

50 to an intense heat and are moreover always cooled by the air which rushes in to sustain the combustion. When the ash pan is shorter than the one shown two sprinklers one in each rear corner is enough but for the largest

55 pans four are needed. At the rear end

of the central compartment I provide another and different type of sprinkler which I have shown in detail in Figs. 9 and 10 and which is designated by the numeral 21 in Figs. 1, 2, 4 and 5. This sprinkler has an upper flat side 22 and a vertical flat end 23 which are connected by means of an arcuate side 24. The sprinkler has two spaced sides 25 and 26. Secured to the end 23 are lugs 27 each of which is provided with a hole 28. The upper side 22 projects forwardly and forms a flange 29. The arcuate side 24 has a series of spaced flanges 30 and below each flange there are two or more holes 31. These holes are so located with respect to the lower edges of the flanges 30 that the upper edges of the holes are in line with the flanges so that the water when it issues through the holes will strike the lower surface of the flanges and be converted into a spray. A pipe 32 connects the sprinkler 21 with the boiler or the injector line and this pipe is also provided with a valve that can be operated from the cab so that the engineer or fireman can turn the water on or off at will. When the valve is open the water which is under full boiler pressure will emerge through holes 31 and will spray the entire central compartment and thoroughly quench any live coals that may be among the cinders. When the doors in the bottom of the compartment are opened the wet ashes drop down on the track and the compartment is thoroughly cleaned by the action of the spray. In case of burning ties the engineer may open the ash pan doors and turn the water into the sprinkler 21 and subject the ties to a fire extinguishing spray.

It will be evident from the above description taken in connection with the drawing that I have provided a simple and effective means for keeping the ash pan clean and for thoroughly wetting the cinders so as to extinguish them and prevent them from setting fire to any combustible material on or along the track.

In Fig. 5 I have shown another type of ash pan in which the side plates 9 are omitted. This ash pan is box-like and has a space for the accommodation of the axle 32. The bottom 33 is hinged in the same manner as in the other pan and the sprinkler 21 is secured to one end in such a manner that it will spray the entire contents of the ash pan.

It has been customary to wet the ashes before they were dumped; at least, most engines have been provided with means intended to accomplish this but the parts have been so located that they would burn out and render the device inoperative.

I consider that I am the first and original inventor of a combination by means of which the fireman by opening one or more valves can clear the ash pan and thoroughly sprin-

kle the ashes. I also consider that I am the first inventor of the type of spray nozzles used in the combination.

Having now described my invention, what I claim as new is:

1. In combination, an ash pan having a central longitudinal compartment adapted to receive ashes and cinders, a flat plate secured to each side of said compartment, and separate sprinklers secured to said plates near the outer corners thereof said sprinklers being adapted to direct inwardly inclined streams of water along the upper surface of the plates whereby cinders which may be lodged thereon will be washed into the central compartment.

2. In combination, an ash pan having a central longitudinal compartment provided with outwardly extending, slightly upwardly inclined plates along its upper edges; sprinklers connected to said plates at the outer corners thereof, each of said sprinklers having one side curved and provided with a

plurality of holes angularly inclined with respect to each other, said holes opening inwardly towards said compartment, and pipes connected to said sprinklers for supplying water under pressure.

3. In combination, an ash pan having a central longitudinal compartment provided with outwardly extending, slightly upwardly inclined plates along its upper edges, a sprinkler secured to each outer corner of said plates, each of said sprinklers having two straight sides making a right angle with each other and a curved side connecting the ends of the straight sides, the straight sides being substantially parallel with the sides and ends of said plates, the curved side having a plurality of holes inclined with respect to each other, means for clamping the sprinklers to the plates, and means comprising pipes for conducting water under pressure to said pipe.

In testimony whereof I affix my signature.

CHARLES A. PRATTE.
